UNITED STATES PATENT OFFICE

161,485

WATCHCASE

David Megar, New York, N. Y.

Application February 23, 1950, Serial No. 8,366

Term of patent 3½ years

(Cl. D42—8)

To all whom it may concern:

Be it known that I, David Megar, a citizen of the United States and a resident of Borough of Manhattan, city, county, and State of New York, have invented a new, original, and ornamental Design for a Watch Case, of which the following is a specification, reference being had to the accompanying drawing, forming a part thereof.

On the drawing:

Figure 1 is a face perspective view of a watch case, showing my new design.

Figure 2 is a top plan view of Figure 1.

Figure 3 is a side view in elevation of the watch case shown in Figure 1, and

Figure 4 is an end view in elevation of the watch case shown in Figure 1.

The back of the watch case is plain while the

opposite side and end views are similar to those shown.

I claim:

The ornamental design for a watch case, substantially as shown and described.

DAVID MEGAR.
